A. P. FRANGIPANE

SOUND BOX

Filed Sept. 23, 1921

Inventor
Anthony P. Frangipane
By his Attorney
James J. Stock

UNITED STATES PATENT OFFICE.

ANTHONY P. FRANGIPANE, OF KINGSLAND, NEW JERSEY, ASSIGNOR TO WILLIAM J. BAUER, OF NEW YORK, N. Y.

SOUND BOX.

Application filed September 23, 1921. Serial No. 502,653.

To all whom it may concern:

Be it known that I, ANTHONY P. FRANGIPANE, a resident of Kingsland, Bergen County, State of New Jersey, and a citizen 5 of the United States of America, have invented certain new and useful Improvements in Sound Boxes, of which the following is a specification.

This invention relates to improvements in 10 sound boxes for phonographs, one of the objects being to provide means to vary the tones; in other words, to soften the tones at will and to a desired degree. To carry out my invention, I provide a device or element 15 to restrain the vibrations of the stylus arm, or arm which imparts vibration to or receives same from a needle. My improved vibration restraining device is adjustable longitudinally of the stylus arm in order that it 20 can be caused to contact with the restraining element to a desired extent. My improved device can be incorporated with a sound box or may be in the form of an attachment.

I will now proceed to describe my invention 25 in detail, the novel features of which I will point out in the appended claim, reference being had to the accompanying drawing, wherein:

Fig. 1 illustrates a top plan view of a 30 sound box provided with my improvement;

Fig. 2 is a sectional view thereof, partly in elevation, the section being taken on line 2—2 in Fig. 1;

Fig. 3 is an enlarged sectional detail 35 view, the section being taken on line 3—3 in Fig. 1;

Fig. 4 is a similar view, the section being taken on line 4—4 in Fig. 1;

Fig. 5 is a top plan view of a modified 40 form of my invention; and

Fig. 6 is a side view thereof.

As herein arranged, my invention consists of a bridge or guide 7 arranged to extend diametrically of a sound box 8 in parallelism with the stylus arm 9. The bridge 45 7 in this instance is made up of two parallel rails 10 acting as guides for a block 11 slideable longitudinally of the bridge 7. The block 11 is provided with longitudinally disposed rabbet grooves 12 to receive the rails 10. To operate the block 11 longitudinally of the bridge 7, and arm 9, I provide a gear 50 13 engaging a rack 14 cut in the block 11.

The gear 13 is carried by a shaft 15 rotatably supported by a lug 16 extending from a 55 rail 10. The shaft 15 carries a thumb-wheel 17, the hub 18 of which is recessed as at 19 to receive a spring 20. The spring 20 acts to take up any slack that may exist, thereby preventing chattering or rattling of 60 the gear 13 and its associated parts. The bridge 7 may be secured to the sound box 8 by screws 21 or it may be constructed as illustrated in Figs. 5 and 6 so that it can be 65 attached to sound boxes of various diameters. When arranged for attachment to sound boxes of various diameters, the bridge portion 22 (Figs. 5 and 6) will be provided with brackets 23, 24 and 25, each carrying a set screw 26 by which means the 70 bridge can be attached to various sound boxes. In other respects the two forms are 75 identical.

To restrain the vibrations of the arm 9, I provide block 11 with a pad 27 slotted 75 longitudinally thereof as at 28 to receive arm 9, as indicated in Figs. 2 and 3. While vibrating, the sides of the arm 9 will rub against the sides of the slot 27, which will be made of some soft material, such as felt 80 or rubber. The pad 27 acts the same as a mute for a violin; as a matter of fact, it is a mute. The pad or mute 27 can be caused to engage arm 9 to any desired extent by adjusting the block 11 longitudinally of 85 the arm 9, by manipulation of thumb wheel 17. The greater the surface engaged by the mute, the lower the tones will be. In other words, the tones can be modulated to a desired extent by merely adjusting the block 90 11 longitudinally of the arm 9. The mute also acts to eliminate scratching of the needle and also blast tones.

What I claim and desire to secure by Letters Patents is:—

A sound box having a stylus arm, a bridge 95 extending diametrically across said box and disposed parallel with the stylus arm, a carrier slidably mounted on said bridge, a filling in said carrier adapted to engage the opposite sides of said stylus arm, and means for moving said carrier longitudinally of said stylus arm, whereby a varying length 100 of said stylus arm may be in contact with said filling.

ANTHONY P. FRANGIPANE.
